(57) **CLAIM**

The ornamental design for an access control gate, as shown and described.

DESCRIPTION

FIG. 1 is a perspective view of an access control gate showing my new design with a gate of the access control gate in a first configuration;

FIG. 2 is a perspective view thereof with the gate of the access control gate in a second configuration opposite the first configuration; and,

FIG. 3 is a perspective view thereof with the gate of the access control gate in a third configuration intermediate of the first and second configurations.

The broken lines indicate environment and portions of the access control gate and form no part of the claimed design.
